UNITED STATES PATENT OFFICE.

DAVID FRANK, OF ALLEN TOWN, PENNSYLVANIA.

RAILROAD-SIGNAL.

SPECIFICATION forming part of Letters Patent No. 278,281, dated May 22, 1883.

Application filed June 3, 1882. (No model.)

To all whom it may concern:

Be it known that I, DAVID FRANK, of Allentown, in the county of Lehigh and State of Pennsylvania, have invented certain new and useful Improvements in Railroad-Signals; and I do hereby declare the following to be a full, clear, and exact description of the invention, such as will enable others skilled in the art to which it pertains to make and use it, reference being had to the accompanying drawings, which form part of this specification.

My invention relates to railroad block-signals; and it consists in the novel construction, combination, and arrangement of devices used, whereby a series of signal-boards are operated automatically by the moving trains upon the tracks of the railroad.

The object of my invention is to provide a system of signals along the line of the railroad, whereby the engineer on the locomotive, running at full speed, may at any time see whether the track on which his train is running is clear of trains traveling in the same direction, or of meeting trains moving in the opposite direction, for a safe distance, and thus avoid accidents frequently occurring around curves, where the view of the engineer is limited by either natural or artificial obstructions. By this system it also becomes unnecessary in case of delays or stoppages of trains for the rear flagman to leave his train to give the signal to approaching trains, the primary object being to run the greatest number of trains safely in the shortest space of time over the railroad.

In the accompanying drawings, in which similar letters of reference indicate like parts, Figure 1 is a plan view of a railroad-track showing my improvements applied thereto. Fig. 2 is an elevation of the signal-stand in connection with the outer rail or track, showing the manner of the attachments. Fig. 3 is a side elevation of the same. Fig. 4 is a section and plan view of the signal-stand in connection with the outer rail of track and its attachments. Fig. 5 is a horizontal section through the upper part of the signal-stand above the double crank. Fig. 6 is a partial elevation of intermediate signal-stands. Fig. 7 is a side elevation of the lever draw-beam, and Fig. 8 is a side or end elevation of a bracket

with pulleys attached for the wire bearings. Fig. 9 is a plan view, showing the connection between the blocks. Fig. 10 is a plan view of two blocks connected.

In the drawings, A represents the signal-stand, made of cast or wrought iron, which is secured by bolts or otherwise to projecting sills or ties E, same as the ordinary switch-ties. The stand is provided with pedestal block or bearings a, in which the signal-post B is free to revolve, having a pivotal bearing in the bottom plate, A', of the stand.

Attached to the signal-post, at the upper part of the stand, is a double-armed crank, B', with holes in the one arm for the attachment of the wires operating the signal-board, the other arm being shaped so as to limit the movement of the crank to a certain arc or distance, so as to confine the signal-boards to the turning of a right angle. The signal-board C is made of wrought-iron sheet metal, and to be painted red for the danger signal. The signal-board is to be connected with the signal-post by means of a suitable bar, c, of such length as best adapted to the locality, the lower end of which is provided with a socket and suitable fastening, S', for the attachment to the post.

On the lower end of the signal-post B is mounted the arm b, which is allowed a movement through a quarter of a circle, independently of the post B, being connected thereto by a chain, N', which passes over the sheaves N², secured to the stand A, and is secured to the arm B², which projects from near the upper end of the post B, at right angles to the signal-board, as shown at Figs. 3 and 9, and said arm b is provided with holes for the adjustment and attachment of the connecting-arm F, and to which arm b also is attached the wire operating the series of signal-boards comprised in the block. The connecting-arm F is slotted at its ends and is connected by bolts to the movable arm b and the crank-arm G'.

The rock-shaft G, which is made of wrought-iron, may be of any length to suit circumstances, and is supported on pillow-blocks Q or other suitable bearings attached to the bearing-plates D and J, which also serve as bearings for the signal-stand and rails I I, to which

the same are properly secured by bolts or otherwise, as well as to the ties on which they rest. The rock-shaft G has also a segmental-shaped crank-arm at the opposite end from the crank-arm G', immediately under the lever-beam H, which, by being raised or lowered, operates upon and gives movement to the crank, which movement is transmitted to the connecting-arm F and arm b, operating the signal-boards. This lever-beam H will be made about twenty-six feet long, or of such a length that a wheel or wheels will be bearing down upon it as long as there is a car or train passing over it. As soon as the last car has passed by, the signals, except on post B, show a clear track-section. The signal on post B remains at "danger" because of the loosely-mounted arm b, which, while being connected to the lever-beam and to the post B through the chain N' and arm B², allowing it an independent movement through a quarter of a circle, is retracted by the weight O, attached to the connecting-wire W through the arm B' and chain M at the last stand Z in the block to which said arm b belongs, and being connected to the rearward signal-boards causes them to be set at "safety" without altering the position of the post B. The rails I I may be of the usual form, with the flanges on one side cut off or omitted, and take the place of an ordinary rail firmly secured to the ties with spikes and to the cast-iron plate J, on which are cast lugs j j for the reception of the flanges. These rails I I are firmly bolted together at the ends, with blocks i inserted between them, to form a groove or channel for the insertion of the lever-beam H. This beam is shaped as shown in Fig. 7, and in cross-section between the rails, as in Fig. 2. One end is slightly inclined downward, terminating in a downward projection, through which is inserted a bolt, when in position, to prevent the beam from jumping out of its groove or channel between the rails. This bolt x, as shown in Fig. 3, passes through the lever below the lower edges of the rails I, and while it allows the lever to have a free vertical movement it prevents this end of the lever from getting out of position. Near the opposite end is also a slight incline downward, with an elongated hole in the downward projection and terminating with a heel, h. The bolt, which serves as a pivot for the lever to oscillate upon, is passed through this elongated hole or slot. This heel extends under and engages with the block inserted between the two rails I I, thus securing the beam in case the bolt through h should disengage itself. This beam may be made of steel or of wrought-iron steeled on top. A block with a strong spring, K, is placed under the one end of the lever-beam, as shown in Fig. 7, to keep the beam in proper position—that is, the lower part of the incline at both ends to be on a line with the top of the ordinary rails R.

Guard-rails P P are placed opposite the rails I I, as shown in Fig. 1, to prevent cars from

jumping the track in case the beam H should, for some reason, not perform its function. Signal-stands, with their connections, are erected, as shown in Fig. 1, at suitable points along the road; also, intermediate signal-boards erected on stands L, as shown on Fig. 6, or bracketed stand secured to telegraph-poles, all connected together by a wire, W, extending from one end of signal-section to the other. The wire is connected at one end to the movable arm b, near which a swivel, S, with spring, is inserted to counteract any sudden jarring. From thence it is connected with the first intermediate signal-board, as shown at L, Fig. 8, 1, close to which a screw-swivel is inserted to regulate the expansion and contraction of wires. The wire is then continued from one intermediate signal-board to the other until the last one in the section is reached, at which point the wire is attached to the doubled-armed crank B', operating the last signal-board in the block. Connected with the crank B' is a chain, M, to which is suspended the weight O, or suitable springs sufficient to keep the wire taut and lift the draw-lever beam to the position shown in Fig. 3, this construction being shown at Fig. 9. The chain is drawn over pulleys N, secured to the top of stand A. To give bearing or support to the wire between intermediate stations, bracketed pulley-bearings are provided, as shown in Fig. 8.

The operation of my device is as follows: A train moving in the direction of the arrow-head in Fig. 1, as the wheels come to the first rails I I they come in contact with the inclined portion of the draw-lever beam H, the weight presses the lever down, and, bearing upon the crank G, the motion is transmitted, as already described, to the wire, and all the signal-boards to the rear of the post B connected together indicate "danger," or are turned in relation to the track, as indicated in Figs. 2 and 3, until the last truck has passed over the beam, when the weight at the farther end of the wire will again bring the signal-boards to their proper positions, showing the track clear and each series of boards connected, thus giving the signals automatically to approaching trains coming in the same direction; but, owing to the pivoted arm b, the terminal post B, with its signal-board set to indicate "danger," is allowed to remain until the train reaches the lever next in advance of terminal post B, on passing which the signal of said terminal post B will be set at "safety" by means of the connecting-wire W, and the signal-boards in this block set at "danger," the same operation being repeated in block after block as the train advances. In the event of an advancing train running in the opposite direction to the arrow shown in Fig. 10 the signals will be set to indicate "danger" a block ahead precisely as when running in the former instance. This signal is intended to be used upon single or double tracks or at crossings, and to signal to trains on ahead or in the rear, trains traveling in the direction

of the arrows signaling to the rear, and those traveling in the opposite direction signaling ahead. Where a single track is used, when one treadle is depressed no effect is produced upon the other treadle. It matters not upon which end of the treadle the wheels run, for the treadle sinks down quietly under the heavy pressure of the wheels.

Having thus described my invention, what I claim is—

1. The combination of the rails *II*, connected at both ends with blocks *i i*, and plates *J*, having lugs *j*, with draw-lever beam *H*, constructed and arranged to operate substantially as shown and described.

2. In combination with the lever-beam *H*, the crank-arms *g* and *G'*, attached to the connecting-rod *G*, the connecting-arm *F*, and the movable arm *b*.

3. In combination with the movable arm *b*, the wire *W*, with its swivels *S* and *T*, connected with the double-armed crank *B'*, chain *M*, and weight *O*.

4. In combination with the wire *W* and the movable arm *b* and crank-arm *B'*, the signal-stand *A*, the post *B*, and the signal-board *C*, also intermediate posts, *L*, and bracketed wire bearings *U*, or equivalent means for operating the same, substantially as shown and described, and for the purpose herein set forth.

In testimony whereof I affix my signature in presence of two witnesses.

DAVID FRANK.
